UNITED STATES PATENT OFFICE.

WILLIAM FITZPATRICK, OF GIRARD, KANSAS.

FIRE-ESCAPE.

SPECIFICATION forming part of Letters Patent No. 375,279, dated December 20, 1887.

Application filed July 25, 1887. Serial No. 245,245. (No model.)

To all whom it may concern:

Be it known that I, WILLIAM FITZPATRICK, a citizen of the United States, residing at Girard, in the county of Crawford and State 5 of Kansas, have invented a new and useful Improvement in Fire-Escapes, of which the following is a specification.

My invention relates to fire-escapes; and it consists in the construction and arrangement 10 of the parts of the same, which will be more fully set forth hereinafter, and pointed out in the claims.

The object of my invention is to provide a fire-escape which is simple and effective in its 15 construction and operation, strong and durable, applicable for use in connection with any form of building, and positive in its result. I attain this object by the device illustrated in the accompanying drawings, wherein like let- 20 ters of reference indicate similar parts in the several views, and in which—

Figure 1 is a perspective view of a top portion of a building with my improved fire-escape applied in connection therewith. Fig. 25 2 is a detail view of one of the anchors, showing the same attached to the corner of a building. Fig. 3 is a perspective view in detail of a traveler and cage shown in connection therewith.

30 A A indicate suitable metallic anchors constructed of strips of metal adapted to fit over the corners of buildings and which are mounted upon bearing-blocks *a*, which are secured to the building to cause the said anchors to project outwardly for the reception of links *b*, connected to the top portion of sheaves or pulleys *B*. The bearing-blocks *a* will be arranged 35 at the corners of the building and secured to the same bolt which secures the ends of the anchors A A. A cable, C, is attached extending across the face or end of the building, as shown. Upon this cable C a traveler, D, is mounted, and consists of two plates, *d*, having sheaves or pulleys *d'*, mounted on each side 40 thereof and in the upper part thereof. The pulley *d'*, mounted in the upper part of the traveler D, is adapted to bear and travel on the cable C across the side or end of the building, as will be readily understood. Suitable 45 guy-ropes, E E, are passed up through the rear of and over the side pulleys, *d'*, in the

traveler D, and thence through the two sheaves B B. The two ends of the guy-ropes E E, which extend down from the lower portion of the traveler, are secured to the top portion of 55 a cage, F, which is adapted to travel in front of the windows for the purpose of allowing the occupants of the building to escape therefrom by getting into the said cage, which will be constructed of such size and of such materials applicable for the purpose for which it is to be used. When it is adapted to lower the said cage to the ground, it is drawn down by means of a rope, F', which is connected to the top portion of the cage adjacent to the 60 point of connection of the two guy-ropes E E. When the cage is thus drawn down, the guy-ropes are slackened and allowed to be drawn up as the said cage is connected to the other end of the said rope. 70

It will be understood that the ends of the guy-ropes E and F' will be at all times in close proximity to the ground when in use, and when in disuse the cage will be elevated and arranged at one side or corner of the building, 75 the guy-ropes being fast over suitable cleats in close proximity to some window or opening and readily accessible.

Articles of clothing, furniture, or any other articles desired to be removed from the building 80 may be readily transported to the ground by connecting suitable ropes to the ends of the guy-ropes E in place of the cage F, as will be readily understood.

As shown at B' in Fig. 1, a traveler may be 85 used having only an upper and a lower sheave; but I prefer to use the form of traveler here-tofore described.

The novelty and utility of my device being 90 obviously apparent, it is unnecessary to further enlarge upon the same herein.

In place of the ropes shown and described I may employ chains with equal effect. I do not wish to be limited to the use of my invention as a fire-escape, as it may be advantageously employed for other purposes, such as 95 a painter's scaffold.

Having thus described my invention, I claim—

1. The combination, with the anchors A, the 100 bearing posts or blocks *a*, upon which said anchors are mounted, of the sheaves B, secured

to said anchors by means of links *b*, and the cable C, secured to the bearing-blocks *a*, substantially as described.

2. The combination, with the anchors A, 5 mounted on the bearing posts or blocks *a*, of the sheaves B, the links *b*, connecting said sheaves to the anchors A, the cable C, the traveler D, constructed with two or more sheaves, *d'*, arranged therein, and the guy-
10 ropes E E, substantially as described.

3. The combination, with the anchors A A, mounted as set forth, of the sheaves B B, connected to said anchors by means of the links *b*, the cable C, the traveler D, having the

three sheaves *d'* mounted therein, the guy- 15 ropes E, passing over the side sheaves, *d'*, in the traveler D and passing through the sheaves B, the cage F, secured to the opposite ends of said guy-ropes E, and the guy-rope F', sub-
stantially as described. 20

In testimony that I claim the foregoing as my own I have hereto affixed my signature in presence of two witnesses.

WILLIAM FITZPATRICK.
